UNITED STATES PATENT OFFICE.

RALPH P. SPOONER, OF CORNWALL-ON-THE-HUDSON, NEW YORK, ASSIGNOR TO BARTON & SPOONER, OF CORNWALL-ON-THE-HUDSON, NEW YORK, A FIRM.

DESIGN FOR A WOODEN MUG.

No. 37,902.

Specification for Design.

Patented March 20, 1906.

Application filed February 10, 1906. Serial No. 300,542. Term of patent 7 years.

To all whom it may concern:

Be it known that I, RALPH P. SPOONER, a citizen of the United States, and a resident of Cornwall-on-the-Hudson, in the county of Orange and State of New York, have invented a new, original, and ornamental Design for a Wooden Mug, reference being had to the accompanying drawing, in which the figure is a perspective view of the wooden mug, showing my design.

I claim—
The ornamental design for a wooden mug as shown.

RALPH P. SPOONER.
